(57) **CLAIM**

The ornamental design for a post-procedural mask, as shown and described.

DESCRIPTION

FIG. 1 is a perspective view of a post-procedural mask according to a first embodiment of the present invention; FIG. 2 is a front view thereof;

FIG. 3 is a rear view thereof;

FIG. 4 is a right side view thereof, left side view being a mirror image;

FIG. 5 is a perspective view of a post-procedural mask according to a second embodiment of the present invention; FIG. 6 is a front view thereof;

FIG. 7 is a rear view thereof;

FIG. 8 is a right side view thereof, left side view being a mirror image;

FIG. 9 is a perspective view of a post-procedural mask according to a third embodiment of the present invention; FIG. 10 is a front view thereof;

FIG. 11 is a rear view thereof;

FIG. 12 is a right side view thereof, left side view being a mirror image;

FIG. 13 is a perspective view of a post-procedural mask according to a fourth embodiment of the present invention; FIG. 14 is a front view thereof;

FIG. 15 is a rear view thereof;

FIG. 16 is a right side view thereof, left side view being a mirror image;

FIG. 17 is a perspective view of a post-procedural mask according to a fifth embodiment of the present invention; FIG. 18 is a front view thereof;

FIG. 19 is a rear view thereof;

FIG. 20 is a right side view thereof, left side view being a mirror image;

FIG. 21 is a perspective view of a post-procedural mask according to a sixth embodiment of the present invention; FIG. 22 is a front view thereof;

FIG. 23 is a rear view thereof; and,

(Continued)

FIG. 24 is a right side view thereof, left side view being a mirror image.

The broken lines in the drawings are for illustrative purposes only and form no part of the claimed design. For example, broken lines formed by equal length dashes show unclaimed portions of the design. Broken lines formed of unequal length dashes (i.e., dash-dot) show boundaries between claimed and unclaimed portions of the design.
